BOOT OR SHOE AND METHOD OF MAKING
THE SAMESamuel Bown, St. Louis County, Mo., assignor
to International Shoe Company, St. Louis, Mo.,
a corporation of Delaware

Application November 11, 1933, Serial No. 697,573

8 Claims. (Cl. 36—3)

This invention relates to boots or shoes and to the method of making the same, and has special reference to boots or shoes in which the vamp comprises an outer member and a lining member and an interposed box toe member, the said three members being assembled and secured in a novel relationship, and the outer member being characterized by novel functional and ornamenting features.

10 Objects of the invention are to provide a vamp structure for boots or shoes including an outer member and a lining member therefor secured together in proper cooperative relationship and having openings formed through both of said members after said members are secured together; to provide a box toe member for application and attachment between the forepart of said inner and outer members after said inner and outer members have been secured together and subsequently perforated; and to provide means for securing said box toe member between and in connection with both said inner and outer members in a predetermined relationship to said openings.

25 Another object of the invention is to provide an improved method of making said vamp structure, comprising the steps of first securing together the inner and outer members in a predetermined relationship; perforating certain areas of both members to form openings through both members after said members have been secured together; detaching the forepart of said members and placing between them an imperforate box toe member in a position to leave unobstructed certain of said openings; and securing both said inner and outer members in connection with said interposed box toe member.

30 A further object of the invention is to provide ornamenting perforations or outlines upon the surface or in the body of the forepart of the outer member that overlies the interposed box toe member.

35 Other objects and numerous advantages of this invention should be apparent from the following description, reference being made to the annexed drawings, in which—

40 Fig. 1 is a plan view showing the blank forming the outer member of the vamp structure superimposed upon and attached to the inner member before said two members are perforated and before placement of the interposed box toe member, portions of the outer member being broken away.

45 Fig. 2 is a longitudinal sectional view of the vamp structure on the line 2—2 of Fig. 1.

Fig. 3 is a plan view showing the imperforate box toe member.

Fig. 4 is a side edge elevation of the box toe member.

Fig. 5 is a plan view similar to Fig. 1 showing the perforations that have been formed through the superimposed outer and inner members after they have been attached together and also showing a portion of the interposed box toe member.

Fig. 6 is a longitudinal sectional view on the line 6—6 of Fig. 5.

Fig. 7 is a plan view of the vamp structure with parts of the outer member broken away to disclose the imperforate interposed box toe member closing certain of the perforations through the inner and outer members.

Fig. 8 is a sectional view on the line 8—8 of Fig. 7.

Fig. 9 is a view similar to Fig. 7 showing the subsequently formed perforations through the interposed box toe member in registration with the perforations through the inner and outer members.

Fig. 10 is a longitudinal sectional view on the line 10—10 of Fig. 9.

In making my improved vamp structure for boots or shoes, I provide an outer member 1 and an inner member 2 of appropriate flexible and pliable material and of approximately the same size and shape. In making vamp structures for shoes a tongue may be attached thereto comprising an outer section 3 and an inner section 4 superimposed upon each other and attached together along their exposed marginal edges by stitches 5. The forward end of the outer section 3 may be extended between the marginal portions of the outer and inner members 1 and 2 of the vamp structure (Fig. 3) and the forward end of the inner section 4 of the tongue may be extended against the inner surface of the member 2 and attached thereto by stitches 6, the outer section 3 being attached to the marginal edge of the member 1 by stitches 7. The stitches 5 may be applied after the sections 3 and 4 are attached to the members 1 and 2, respectively.

A heavy coat 8 of cement is then applied upon that surface of the inner member 2 which is adjacent to the outer member 1 rearwardly from about the line 9 and a relatively light or thin coat 10 of cement is applied upon the same surface of the inner member 2 forwardly beyond the line 9. The cement 8 may also be placed over the surface of the inner tongue section 4 that is to be covered by the outer tongue section 3.

If desired, a number of ornamenting configurations 11 may be formed upon the exposed surface or in the body of the forepart of the outer member 1 before the members 1 and 2 are brought together in superimposed relationship.

It should be understood that the inner surface of the outer member 1 may also be provided with a coating of adhesive cement corresponding to the coating 8-10, if such amount of cement is needed.

10 Next, the outer member 1 having the tongue section 3 attached thereto is superimposed upon the inner section 2 in matching relationship and the two sections are adhesively united by the cement 8-10, which may be a cold quick drying cement particularly appropriate for this use. Sufficient pressure is applied to the two members, including the tongue sections 3 and 4, to obtain a good adhesive connection, which is particularly strong over the area covered by the cement 8 but 20 is readily separable over the area covered by the lighter cement 10 in front of the line 9.

Next, numerous ventilating perforations 12, which may also constitute ornamentations, are formed through the attached members 1 and 2 over a considerable portion of the area rearwardly from the line 9 and over a portion of the area 25 in front of the line 9.

Next, the forward ends or toe portions of the members 1 and 2 are detached by pulling said 30 portions apart to break the attachment over the area covered by the lighter cement 10 in front of the line 9, and a preformed box toe member 13 is placed in proper position upon the inner member 2 across the ornamenting perforations 11 and 35 across the perforations 12 that are in front of the line 9.

Both surfaces of the box toe member 13 may be coated with cement 14, or the surfaces of the members 1 and 2 that are adjacent to said box 40 toe member may be coated with this cement.

Next, the separated forward portions of the members 1 and 2 are pressed toward each other and are adhesively united to the box toe member 13 and to each other along their marginal edges 45 beyond said box toe member, as should be understood by reference to Fig. 5.

Next, the two members 1 and 2 are attached together by rows of stitches 15 arranged in ornamenting configuration with respect to the holes 12 and extended forwardly beyond the line 9, so 50 that parts of said rows of stitches pass through the three members 1, 2 and 13 and thereby strengthen the attachment of these members and cooperate with the cement to hold said members in relatively fixed relationship.

As already explained and as should be apparent from Fig. 7, the box toe member 13 extends across and closes certain of the holes 12, namely, those holes 12 which are in front of the line 9. 60 After the box toe member 13 has been interposed between and attached to both members 1-2, holes 16 in continuation of the holes 12 are formed through that portion of the box toe member 13 which closes any of the holes 12, thus obtaining an arrangement in which the holes 12 and 65 16 constitute openings through the three members 1, 2, and 13.

Vamp structures of this type may be manufactured rapidly and with facility and the different members assembled without difficulty since there is no necessity for observing care in placing the members together to register with pre-formed holes in the respective members. The cement 8 will hold the members 1 and 2 in proper 70 relationship with respect to each other for rapid 75

placement and attachment of the box toe member 13 and thereafter the attaching and ornamenting stitches 15 may be easily applied and the holes 16 formed.

This vamp structure may then be embodied 5 in a shoe by usual methods. A shoe that will afford ease and comfort when worn is thus obtained because no reliance for stiffening the toe portion is placed upon the flexible and pliable inner member 2. On the contrary, the inner 10 member 2 may be of comparatively soft material, the necessary degree of stiffness being obtained by the box toe member 13.

The structure and the method of making the same may be varied within the scope of equivalent limits without departure from the nature and principle of the invention.

I claim:—

1. A vamp structure comprising inner and outer members having their rear portions adhesively attached and having registering perforations through said rear portions and the forepart of said outer member having perforations therethrough opposite an imperforate portion of said inner member, a box toe member interposed between the forepart of said inner and outer members and having an imperforate portion opposite said last named perforations that are through the forepart of said outer member and having perforations therethrough registering with certain of said first named perforations that are through said inner and outer members, and stitches passing through the rear portions of said inner and outer members and also extending forwardly and extending through the forepart of 30 said inner and outer members and the rear portion of said interposed box toe member.

2. The method of making a shoe vamp structure comprising adhesively uniting the rear portions of inner and outer members, forming openings simultaneously through the rear portions of said inner and outer members, placing a box toe member between the foreparts of said inner and outer members, and then stitching together the rear portions of said inner and outer members 45 and said box toe member remote from the outer edges thereof.

3. The method of making a shoe vamp structure comprising adhesively uniting the rear portions of inner and outer members, forming openings simultaneously through the rear portions of said inner and outer members, placing a box toe member between the foreparts of said inner and outer members, then stitching together the rear portions of said inner and outer members 55 and the rear portion of said box toe member remote from the outer edges of said members, and then forming openings in the rear portion of said box toe member in registration with certain of 60 said openings through said inner and outer members.

4. The method of forming a shoe vamp structure including the steps of perforating an outer member, attaching the rear portion of said outer member to the rear portion of a matching inner 65 member, forming perforations through the rear portions of said two members, adhesively securing a box toe member between the foreparts of said inner and outer members across said first named perforations that are through the forepart of said outer member and across certain of 70 said perforations that are through said inner and outer members, and then forming openings through said box toe member in registration with said perforations that are through said inner 75

and outer members and across which said box toe member extends.

5. The method of forming a shoe vamp structure including the steps of perforating an outer member, attaching the rear portion of said outer member to the rear portion of a matching inner member, forming perforations through the rear portions of said two members, placing a box toe member between the foreparts of said inner and outer members across said first named perforations that are through the forepart of said outer member and across certain of said perforations that are through said inner and outer members, then forming openings through said box toe member in registration with said perforations that are through said inner and outer members and across which said box toe member extends, and stitching together the rear portions of said inner and outer members remote from the outer edges thereof and adjacent to said first named perforations.

6. The method of forming a shoe vamp structure including the steps of perforating an outer member, attaching the rear portion of said outer member to the rear portion of a matching inner member, forming perforations through the rear portions of said two members, placing a box toe member between the foreparts of said inner and outer members across said first named perforations that are through the forepart of said outer member and across certain of said perforations

that are through said inner and outer members, then forming openings through said box toe member in registration with said perforations that are through said inner and outer members and across which said box toe member extends, 5 stitching together the rear portions of said inner and outer members remote from the outer edges thereof and adjacent to said first named perforations, and also stitching together said inner and outer members and the rear portion of said 10 box toe member remote from the outer edges thereof.

7. In the method of making shoe uppers and the like, the steps of uniting an inner and an outer member throughout their common extent, 15 then separating them through a predetermined portion of this extent and inserting a stiffener between the separated portions, and finally uniting said separated portions about said stiffener.

8. In the method of making shoe uppers and the like, the steps of uniting an inner and an outer member relatively inseparably throughout a predetermined portion of their extent, and relatively separably throughout an additional portion, whereby they may be subjected to further 25 operations as a unit, and then separating them in their relatively separable portion whereby an insert may be located between them in such portion.

SAMUEL BOWN. 30
